UNITED STATES PATENT OFFICE.

MOSES G. FARMER, OF NEW YORK, N. Y.

TELEPHONE.

SPECIFICATION forming part of Letters Patent No. 351,258, dated October 19, 1886.

Application filed June 11, 1886. Serial No. 204,838. (No model.)

To all whom it may concern:

Be it known that I, MOSES G. FARMER, a citizen of the United States, and a resident of New York, in the county and State of New York, have invented certain new and useful Improvements in Telephones, of which the following is a specification, reference being had to the drawings accompanying and forming a part of the same.

My invention consists in a novel form of telephone-receiver, constructed with a view to securing more pronounced vibrations of the diaphragm, and a consequent more audible reproduction of the sound-waves transmitted as electrical impulses or undulations over a telephone-line.

The ordinary form of telephone receiver has a magnetic diaphragm; but in lieu of this a non-magnetic diaphragm may be employed, to which a magnetic armature is attached. My apparatus belongs to this latter class of telephones; but in lieu of an ordinary magnet and armature carried by the diaphragm it has a series or system of coils, forming a compound helix, in which is suspended a core of special construction, which is attached to the diaphragm.

An apparatus to embody these features with the general arrangement above stated may obviously be constructed in many different ways. In illustrating my invention, however, I shall confine myself to the description of the best and most practicable form of apparatus which is at present known to me, and which contains in itself certain features that are novel and that contribute to the efficiency and usefulness of the instrument.

The accompanying drawings show the details of this instrument, Figure 1 being a horizontal section of the device, taken just above the coils; Fig. 2, a central vertical section of the same, Figs. 3 and 4 being views in elevation of the parts that make up the armature and core; and Fig. 5 is a diagram of the circuits.

A A' are two circular brass plates secured together by the rods B B and made fast to a stand or base, C. Between the two plates or heads A A' are the coils comprising the compound helix, of which the inner coil, D, is of comparatively coarse wire with but few turns or layers, while the other coil, E, is of finer wire with a large number of turns or layers.

The outer coil, E, may fit loosely over the coil D.

The coil D surrounds a stationary tubular core composed of the soft-iron sections F F. The sections F are shouldered at each end and held apart by the brass or non-magnetic rings f, the core being built up in this way and held firmly together by the heads A A'. Within this tubular sectional core are a series of armatures, G, carried by a light brass or non-magnetic tube, H. The armatures G are short tubes of soft iron formed with flanges g, or otherwise, so as to contain a greater mass of iron at their upper ends. They are of a diameter to fit loosely within the sections F, and are separated from each other by interposed rings of a non-magnetic metal, g'. The armatures are secured to the tube H and the sections F placed over them in building up the core, so that the heads or flanges g will be contained in the spaces between the sections F, and be capable of such movement therein as will permit a limited longitudinal movement of the tube H through the core.

The upper end of the tube H is secured to the center of a diaphragm, I, which is contained in any proper kind of case—for example, a recessed and perforated block, J, of hard rubber—the diaphragm being confined in place by a screw-threaded cover, K, provided with a mouth-piece, L, and fitting down into the recess and the upper side of the block J. The block J is adjustably mounted upon the plate A by the screw-rods N L and binding-nuts m, by means of which it may be slightly raised or lowered to secure the best adjustment of the tube H and armatures G, with reference to the sections F of the stationary core. The lower end of the tube H extends downwardly through the base or stand C, and is held in position by three light and flexible straps, N.

The diaphragm I, I prefer to make of aluminium, and the straps N may be of the same material, though rolled much thinner. Any other elastic substance may, however, be used for the diaphragm. The moving parts, comprising the tube H and its armatures, should be comparatively light and the armatures small in proportion to the sections F, in order that such moving parts may have as little inertia as possible.

In using this instrument the inner coil, D,

is included in a circuit from a small local battery, W, with just sufficient current to magnetize the core. The other coil, E, is connected up in the line L. The effect of the current flowing through the coil D is to magnetize both the sections F of the stationary core and the armatures contained within them, and, by reason of their relative positions, to impart the same polarity to their corresponding adjacent ends. The upper end of each inner core or armature being larger than the lower, and being also somewhat nearer to the lower end of the stationary section next above, is attracted by the core above and repelled by that surrounding it. The current impulses in the coil E, acting upon the core thus effected, tend to produce, by means of this conjoint attraction and repulsion, a movement or vibration of the inner cores or armatures in line with their axis, which vibrations being imparted to the diaphragm reproduce sound-waves corresponding to those producing the impulses.

I find that I can in this way produce a receiver of great efficiency, which will articulate distinctly and audibly, and which is admirably well adapted for long-distance telephoning.

The superior results obtained by this instrument I attribute to a mode of operation brought about by the novel construction and relations of the parts described.

By dividing up the movable armature into several parts in fixed relation to each other, as into the sections G, not only is the conjoint effect in producing vibrations of the diaphragm increased, but the moving parts may be made much lighter than otherwise.

The number of armatures or sections of core may vary, as will be well understood, or a number of coils may be used in place of the single coil E, and the general form of the instrument may be of any kind that will secure the same relations of the parts herein described as comprising the essential elements of the invention.

What I claim is—

1. In a telephone-receiver, the combination, with a diaphragm, of several armatures in fixed relation to each other and rigidly connected to the diaphragm, a local coil for magnetizing the armatures, and a line-coil for imparting movement or vibrations to them, as herein set forth.

55 2. The combination, with a diaphragm, of a local magnetizing-helix and a line-helix, a

stationary sectional core within the magnetizing-helix, and armatures rigidly connected together and to the diaphragm and in position to be acted upon conjointly by the sectional core and the line-helix, as and for the purpose set forth. 60

3. In a telephone-receiver, the combination, with a diaphragm, of two concentric cores and helices, one of said cores being stationary and composed of a number of separated sections, the other core being rigidly attached to the diaphragm, and composed of independent armatures, as herein set forth. 65

4. The combination, with a diaphragm, of a local helix and stationary core composed of magnetically-insulated tubular sections, a series of armatures supported within said tubular sections and rigidly attached to a rod or tube connected with the diaphragm, and a line or fine-wire coil surrounding the local coil, as and for the purpose set forth. 70

5. The combination, with two concentric coils, a stationary core composed of magnetically-insulated tubular sections, and a series of armatures within the tubular sections and rigidly connected to a light rod or tube, of an adjustable case or holder for a diaphragm, and a diaphragm secured therein and connected rigidly with the armature supporting 85 rod or tube, as set forth. 80

6. The combination, with the stationary core composed of the separated tubular sections and the movable core or series of armatures rigidly connected to a rod or tube, each 90 armature being arranged within a corresponding section of core and having a greater mass at its upper end, of a diaphragm connected rigidly with the said rod or tube and coils surrounding the cores, as set forth. 95

7. In a receiving-telephone, the combination, with a diaphragm, of a rod or tube connected therewith and held in position by flexible straps secured to the stand or base of the telephone, a stationary core and a movable 100 core, the latter of which is carried by the rod or tube, and coils or helices surrounding the cores, as herein set forth.

8. In a receiving-telephone, the combination, with a helix and a sectional stationary and sectional movable core, of a diaphragm connected rigidly with the movable core, and means for adjusting the diaphragm, as set forth. 105

MOSES G. FARMER.
